UNITED STATES PATENT OFFICE.

DONALD EVANS PARRISH, OF BUFFALO, NEW YORK, ASSIGNOR TO HERBERT MORRIS INCORPORATED, OF BUFFALO, NEW YORK, A CORPORATION OF NEW YORK.

PLATFORM HOIST.

Application filed August 8, 1925. Serial No. 49,084.

My invention relates to improvements in platform hoists of the type generally used in the basements of buildings for conveying furnace ashes to the street or sidewalk level, and the object of the invention is to devise a hoist which is slidably mounted upon two vertical guides, the platform being raised and lowered by means of a chain block, wherein the lifting effort is exerted vertically in a straight line, and not around a series of pulleys. A further object of the invention is to suspend the hoist platform between the guides so that it will project equidistantly upon either side thereof, the chain block being positioned above one projecting end, the other end being supported by two pairs of rollers, one pair of which are positioned upon each side of the platform, engaging the vertical guides and thus transforming the vertical lifting force into a pair of opposed horizontal forces passing through the axes of the respective upper and lower rollers of each pair. A still further object of the invention is to provide a pair of rollers one on each side of the platform for preventing a side to side or swinging motion thereof, the rollers being on a parallel plane to and running upon the pair of vertical guides.

My invention consists of a platform hoist constructed and arranged all as hereinafter more particularly described and illustrated in the accompanying drawing in which:—

Fig. 1 is a perspective view of my hoist showing it positioned in the corner of a basement in proximity to one of the basement windows through which the ash cans are removed.

Fig. 2 is a horizontal plan sectional view taken through the vertical guide members and showing the hoist platform.

Fig. 3 is a side elevational view of an alternative construction in which the hoist platform does not extend between the vertical guides but is positioned on one side thereof, the roller supporting frames being provided with extensions, to the ends of which the hoisting chains are attached. This form of hoist embodies the same principle as the construction shown in Figure 1 but is preferably used where it is desired to raise the hoist platform to the level of a doorway or a second elevated platform.

Fig. 4 is an enlarged plan sectional view through one of the vertical guides of the

alternative construction shown in Figure 3, a fragmentary portion of the hoist platform being shown.

Like characters of reference indicate corresponding parts in the different views.

1 and 2 are a pair of vertically disposed guides being preferably constructed of angle iron and secured at their base to the floor of the basement by means of embedded plates 3 or any other suitable means, and held in position at the top by a horizontally disposed plate 4 which extends from one of the basement walls and is adapted to support the chain block 5 which is mounted upon a pair of depending brackets 6 which are secured to its under side.

The ash can supporting means consists of a horizontally positioned platform 7 which extends between the vertical guides 1 and 2 and is provided with a pair of upwardly extending sides 8 and 9. 10 and 11 are the lifting chains of the chain blocks and are secured at their lower ends to the respective sides 8 and 9 being attached intermediately of the distance between the inner ends of the sides and the vertical guides 1 and 2.

For supporting the outer end of the platform which projects between the vertical guides, I provide upper and lower rollers 12 and 13 upon the outer faces of the sides 8 and 9. These rollers engage the vertical guides 1 and 2 as clearly shown in Figure 1, that is the upper rollers 12 engage the respective inner faces of the vertical members and the lower rollers 13 engage their outer faces. For holding the platform in transverse alignment with the guides 1 and 2 I provide outwardly extending lugs 14 upon the outer faces of the sides 8 and 9. These lugs being adapted to carry rollers 15 which also engage the respective guides 1 and 2. The plane of the rollers 15 being at right angles to the plane of the rollers 12 and 13 and consequently engaging the side faces of the guides.

In the alternative construction shown in Figures 3 and 4 it will be seen that the platform only extends upon one side of the vertical guides, and is not provided with the side walls 8 and 9. The rollers 12 and 13 are positioned below the platform and are mounted upon frames 16 which have extensions 17 to the ends of which the hoist chains are attached. It will be seen in reference to Figure 4 that in this construction the an-

gle irons which constitute the guides 1 and 2 are turned in the opposite direction to the angle irons used in the construction shown in Figure 1 which permit the roller carrying frames 16 being positioned upon the outer side of the guides, thus facilitating the rapid erection of the hoist.

I am aware that hoists embodying upper and lower rollers engaging the front and rear faces of vertical guide members are at present in use but owing to the fact that the lifting effort is exerted either between the vertical planes passing through the axes of the upper and lower rollers or in the plane passing through the axis of the upper roller, the platform has a tendency to bind as the vertical lifting force is only transformed into a single horizontal force acting through the axes of the lower rollers. In my construction when the load is more or less uniformly distributed over the platform the lifting force acts directly upon the portion of the load positioned about the lifting chains and the lifting effort required to raise the remainder of the load which is positioned upon the outer end of, or the portion of the platform which projects between the guides is transformed into two substantially equal and opposite horizontal forces acting through the axes of the respective upper and lower pulleys. It will be seen in my construction that the lifting effort is more evenly distributed and that by the use of a single chain block with a straight pull on the end less hand chain the operating effort is reduced to the easiest possible motion. Furthermore by mounting the lifting gears directly under the top plate no extra floor space is used. It will be understood that in cases where heavy loads have to be rapidly and constantly lifted that power means may be provided for operating the chain block in lieu of the hand chain without departing from the spirit of my invention.

From the foregoing description it will be apparent that I have devised a very simply

constructed and easily operated platform hoist in which the lifting effort is evenly distributed over the platform in such a way as to positively prevent any possibility of the platform binding or energy being wasted in overcoming friction.

What I claim as my invention is:—

1. A hoist comprising a movable platform, a pair of vertical guide members positioned on either side of the platform intermediately of its length, lower and upper rollers on the platform respectively engaging the front and rear faces of the guide members and supporting the portion of the platform projecting beyond the front faces of the vertical guide members, a pair of rollers each positioned between the horizontal axial planes of the lower and upper rollers and adapted to engage the side faces of the vertical guide members, and platform hoisting means positioned in parallel relation to the vertical guide members engaging the platform at a point intermediate of the rear end of the platform and the rear faces of the guide members so that it supports the portion of the platform extending rearwardly of the guide members.

2. A hoist comprising a movable platform, platform hoisting means engaging the platform in the vicinity of its rear end, a pair of vertically positioned guides through which the forward end of the platform projects, lower and upper rollers on the platform respectively engaging the front and rear faces of the guide members, a pair of rollers each positioned upon the platform and each engaging a side face of a vertical guide member, said sets of rollers constituting a support for the forward end of the platform and a means for preventing side rocking motion of the platform in respect to the guide members, said platform hoisting means constituting a support for the rear portion of the platform.

DONALD EVANS PARRISH.
